UNITED STATES PATENT OFFICE.

SIMON D. PADDACK, OF SAN FRANCISCO, CALIFORNIA, ASSIGNOR TO PADDACK ENGINEERING CORPORATION, OF SAN FRANCISCO, CALIFORNIA, A CORPORATION OF CALIFORNIA.

SOUND-REPRODUCING HORN.

Application filed September 1, 1925. Serial No. 53,775.

To all whom it may concern:

Be it known that I, SIMON D. PADDACK, a citizen of the United States, residing at San Francisco, in the county of San Francisco, State of California, have invented a new and useful Sound-Reproducing Horn, of which the following is a specification, in such full and clear terms as will enable those skilled in the art to construct and use the

10 same.

This invention relates to a loud speaker horn for radio telephones or for phonograph reproducers, and an object of the invention is to produce a very effective horn without unduly increasing its size.

Another object of the invention is to so arrange the horn as to make use of the sonorous qualities of the wood of which both sides of the initial part of the horn is made to im- 20 prove the effect of the tones produced.

Another object of the invention is to provide a casing for the horn which will have an improved appearance over many such casings, and to provide the space within which the radio apparatus may be installed, or inside of which the driving mechanism of the phonograph may be installed if the horn is used on a phonograph.

Another object of the invention is to provide means whereby the entire area of the bottom of the case may be used to improve the tone effect of the sounds passed therethrough, and since the inner and the outer bases are both made of thin wood, they act as extensive sounding boards to prevent the common metallic sounds of such apparatus.

Another object of the invention is to provide means whereby the power of the horn may be regulated, holes with an adjustable damper being used to vary the horn effects.

Another object of the invention is to provide a wooden tongue in the small part of the horn which will be connected to the diaphragm or to the phonograph reproducer box diaphragm to damp the vibrations and thereby reduce the metallic sounds produced.

Another object of the invention is to provide a casing for the apparatus which can be easily removed when necessary to examine the apparatus mounted on the base.

Other objects of the invention will appear as the description proceeds.

An embodiment of the invention is shown in the accompanying drawings in which the same reference numeral is applied to the

same portion throughout, but I am aware that there may be modifications thereof.

Fig. 1 is a front elevation of the apparatus with portions shown in section for purposes of illustration.

Fig. 2 is a top view of the complete apparatus.

The numeral 1 indicates the base of the casing which with the upper sounding board 2 are connected together at their edges by the sides 3 and 4 and by two narrow straps 5 and 6 which form the primary horn with the two sounding boards.

The sounding boards 1 and 2 are made of an exceedingly elastic wood such as spruce, and rubber buttons 7 at each end of the casing serve to hold it at a little distance above the table or case on which the apparatus is installed, and at the wide end of the primary horn there is a curved member 8 which also aids in smoothing out the tones, and directs the vibrations into the horn 9. The horn 9 is secured to the upper casing, and is detachable therewith at will when it is desired to examine the said apparatus installed on the base.

The upper part of the casing 10, which encloses the electrical apparatus, is arranged to have somewhat the appearance of a well known form of clock casing with the horn facing forward. It is secured to the base by snap hooks 11 at each end.

It will also be understood that while the loud speaker unit 12 is mounted on the end of the sounding board 2, that whatever other apparatus may be used must be mounted free of that board to give it the best tone effect.

The loud speaker has the diaphragm 13, which is connected to the wooden tongue 14, by means of a light rod 15 near the small end of the horn between the two sides 5 and 6, the sounding board 2 is provided with a plurality of holes shown in dotted lines under the damper 16.

The damper 16 is pivoted at 17, and is of such a shape as to uncover the holes under the same one at a time as the damper is rotated by the worm 18, which engages the small worm wheel 19 on the damper pivot pin.

The worm 18 is carried by a shaft 20, which has the thumb knob 21 to rotate it; 22 and 23 indicate operating knobs for the electrical apparatus necessary to receive the

radio sounds, but such apparatus per se forms no part of the present invention, hence is not more completely illustrated.

In order to prevent dust from getting into the horn, and give the casing a better appearance, the mouth of the horn at 24 may be provided with a wire or fabric covering 25.

What I claim is as follows, but various 10 modifications may be made in the construction shown in the drawings and above particularly described form within the purview of my invention.

1. In a sound reproducing horn, a pair 15 of sounding boards spaced apart, a pair of spacing members connected to said sounding boards to provide a gradually widening channel forming a primary horn for sounds projected thereinto at the smallest end of 20 such channel, and a horn detachably connected to said sounding board widening in the reverse direction from the primary horn and having its mouth terminating in a substantially vertical plane and extending laterally from the axis of the first horn.

2. A horn for projecting reproduced 30 sounds comprising a pair of flat sounding boards spaced a short distance apart, a pair of narrow spacers connecting the two sounding boards and forming therewith a primary horn, a secondary horn detachably secured to the sounding board and overlying the same, said horn terminating in a substan-

tially vertical plane, extended laterally from the first horn, and a movable damper for 35 opening or closing certain holes in one of the sounding boards forming a portion of the primary horn to vary the tone of the sound produced.

3. A sound reproducing horn comprising 40 a pair of flat sounding boards, a pair of narrow spacers connecting the sounding board and forming therewith a primary horn, a secondary horn detachably connected to the first horn at its widest end, and overlying the same, and a tongue within the primary horn at its narrowest portion to damp the vibrations of the sound reproducing mechanism.

4. A sound reproducing horn comprising 45 a pair of flat sounding boards, a pair of narrow spacing members secured to the sounding boards to hold them a short distance apart to form a primary horn, one of said sounding boards having a series of 50 openings near the smallest end of said primary horn, a pivotally mounted damper adapted to close one or more of said openings, and a secondary horn detachably connected to the first horn and forming an extension thereof over-lying said primary horn.

In testimony whereof I have hereunto set my hand this 22 day of August A. D. 1925.

SIMON D. PADDACK.
